[57] CLAIM

The ornamental design for a sun blocking wearable shield, as shown and described.

DESCRIPTION

FIG. 1 is a front, top and side perspective view of a sun blocking wearable shield showing my new design;
FIG. 2 is a front elevational view thereof;
FIG. 3 is a rear elevational view thereof;
FIG. 4 is a side elevational view thereof, the side opposite being a mirror image of the side shown in FIG. 4;
and,
FIG. 5 is a top plan view thereof, the bottom view being a mirror image of the top view shown in FIG. 5.

FIG. 1

FIG. 2

FIG. 3

FIG. 4

FIG. 5
